UNITED STATES PATENT OFFICE

2,014,880

ELECTROMAGNET STRUCTURE

Bernard M. Cain, Ballston Lake, N. Y., assignor
to General Electric Company, a corporation of
New York

Application August 12, 1933, Serial No. 684,885

9 Claims. (Cl. 171—229)

My invention relates to electromagnet structures and more particularly to improvements in such structures for electrical regulators.

The present invention is an improvement on the invention which is described and claimed in a joint patent application of Benjamin R. Teare, Jr. and Max A. Whiting, Serial No. 642,736, filed November 15, 1932, and assigned to the assignee of the present application. In that application there is disclosed a generator voltage regulator which is arranged to hold substantially constant voltage up to a predetermined value of generator current whereupon with further increases in current the voltage droops relatively abruptly. This relatively abrupt droop is produced by means of a variable reluctance magnetically saturable element and it is pointed out in that application that as this element necessarily has some reluctance even when unsaturated, a slight voltage droop tends to be produced even before the element becomes saturated. Several different ways of compensating for this slight droop are disclosed in that application, but I have found that all of these means produce a compensating effect which varies in a substantially linear manner with the current and as the droop which is to be compensated for varies in a non-linear manner in accordance with the saturation characteristic of the saturable element, as complete compensation as might be desired is not produced.

In accordance with my invention I provide compensating means for the voltage droop caused by the reluctance of the saturable element during the early stages of its saturation by means which acts in a non-linear manner, such for example as by an additional magnetically saturable element. In this manner I found it is possible to achieve substantially complete compensation so that, up to the predetermined current value at which it is desired to produce a relatively abrupt drop in voltage, the voltage will remain substantially constant.

An object of my invention is to provide a new and improved electromagnet structure.

Another object of my invention is to provide a new and improved electrical regulator.

Another object of my invention is to provide improved compensating means for electrical regulators.

A further object of my invention is to provide an improved voltage regulator which acts to hold substantially constant voltage up to a predetermined value of current after which the current droops relatively abruptly.

My invention will be better understood from the following description taken in connection with the accompanying drawing and its scope will be pointed out in the appended claims.

In the drawing, Fig. 1 is a diagrammatic showing of an embodiment of my invention as applied to the electromagnet structure of a generator voltage regulator, and Fig. 2 is a set of curves for illustrating the operation of my invention.

Referring now to Fig. 1, a main electromagnet core 1 is provided which is arranged to be excited by a voltage-responsive main control winding 2 and which has an armature 3 which is mounted on a suitable resilient biasing spring 4. Air gaps 5 and 6 are provided between the core 1 and the armature 3. A pair of control contacts, one of which is on armature 3 and the other of which is fixed are provided, and these contacts are arranged to separate when armature 3 is attracted to the core member 1.

The means for causing the relatively abrupt droop in regulated voltage with increases in current beyond a predetermined value comprises a core member 8 which is arranged to be excited by a current winding 9 thereon. As shown, member 8 is in the form of a yoke and this member cooperates with a saturable section or element 12 of the core 1, which element is shown as a restricted section of the core. Air gaps 10 and 11 are provided between the member 8 and the core 1.

Inserted in the air gap 11 is a magnetically saturable element 17, such as a section of iron. The purpose of this element, the operation of which will be explained more in detail later, is to produce the compensating effect of my invention.

The regulator is shown as arranged to regulate the voltage of a shunt type generator 13 having a shunt field winding 14 in series with which is a regulating resistor 15. The generator 13 is shown connected to charge a storage battery 16. The electrical connections between the regulator and the generator are such that the contacts 1 are connected across the regulating resistance 15 so as to short circuit this resistance when the contacts are in engagement. The voltage responsive main control coil 2 is connected across the generator 13 and the current responsive winding 9 is connected in series with the generator.

The general operation is as follows: Assume that generator 13 is being driven by any suitable prime mover (not shown) and that the generator load circuit is either open or the current therein

is negligible. Under these circumstances, the effect of the current responsive element of the regulator may be ignored and only the voltage winding 2 will be active. As shown, the contacts 7 are in engagement thereby short circuiting the resistance 15 and causing a maximum current to flow through the field winding 14. This increases the voltage of generator 13 until the voltage reaches such a value at which the energization of winding 2 produces sufficient flux to cause a pull on the armature 3 which exceeds the counterpull of the biasing spring 4, thereby separating the contacts 7. As soon as the contacts 7 separate, the resistance 15 is in series with the winding 14 and the current in the field winding decreases, thereby decreasing the voltage of generator 13 and consequently decreasing the energization of winding 2. This weakens the pull of the magnet and the spring 4 snaps the contacts 7 closed. The cycle then repeats itself and this continues at a relatively high rate of speed whereby a substantially constant voltage of generator 13 is maintained.

The operation of the current responsive voltage droop producing feature of the regulator is as follows: As shown, the winding 2 is so connected and wound that it produces a flux which flows through the core 1 and the armature 3 in a counter-clockwise direction. The current winding 9 is so connected as to produce a flux in the core member 8 and the saturable section 12, which is also in a counter-clockwise direction. At low current values this flux merely circulates through the core 8 and the restricted section 12 and as this section has a relatively low reluctance practically all of the flux is by-passed through this section and but a very small portion of the flux flows through the magnetic circuit including the armature 3, because of the fact that the air gaps 5 and 6 are made substantially greater than the air gaps 10 and 11 so that the reluctance of the path through the restricted section 12 is considerably less than the total reluctance of the path through the armature and the air gaps 5 and 6. However, as the generator current increase saturation takes place in the restricted section 12 with the result that its magnetic reluctance increases. The result of this action is that a greater and greater percentage of the flux produced by the winding 9 will tend to flow across the air gaps 5 and 6 and through the armature 3. As the direction of this flux will be the same as the direction of the flux produced by the winding 2, the winding 2 will require less energization to maintain the same value of total flux across the air gaps 5 and 6 and as the action of the regulator is to try to maintain a constant value of flux across these air gaps the result will be that the regulated voltage will decrease.

As explained in the above referred to joint patent application, it has been found that even though the reluctance of section 12 is low at low current values, nevertheless, it is appreciable, so that an appreciable amount of flux crosses the air gaps 5 and 6 and traverses the armature 3. This causes a change in calibration of the regulator resulting in an objectionably premature voltage droop but it was found that by properly proportioning the air gap 11, sufficient leakage flux would be produced by the reluctance of the air gap 11 to produce partial compensation for this droop. The action of this leakage flux is such that it enters the sides and ends of the armature 3 adjacent its contact 7 and then returns through the air gaps 5 and 6 in parallel.

The flux returning through the air gap 5 will be cumulative with respect to the main flux while the flux returning through the air gap 6 will oppose the main flux and as the reluctance of gaps 5 and 6 is substantially equal, the leakage flux 5 will divide substantially equally between these two air gaps. Due, however, to the fact that air gap 6 is further away from the effective pivot of the armature than air gap 5 the effect of the leakage flux will be stronger at air gap 6 than 10 at air gap 5, and as the effect is to weaken the pull of the main magnet at air gap 6 and to strengthen it at air gap 5 the total effect of the leakage flux will be to weaken the pull on the armature 3 as the current increases, and this 15 tends to compensate for the increase in flux through the air gaps 6 and 5 caused by the reluctance of section 12 at low current values.

I have found, however, that the above described compensating action of the leakage flux 20 caused by a proper proportioning of the air gap 11 has a substantially linear effect with changes in current, whereas the droop producing effect of the reluctance of section 12 is non-linear. Consequently it is impossible to secure correct, or 25 substantially complete, compensation with such an arrangement. However, I have found that by inserting a magnetically saturable element, such as an iron member 17 in the air gap 11, I can secure substantially complete compensation. 30

The action of section 17 is as follows: During low current values element 17 is unsaturated and air gap 11 is substantially magnetically short circuited so that there is substantially no leakage flux produced, which is as it should be because 35 at very low current values I have found that the reluctance of the section 12 is so low as to be negligible. However, at intermediate values of current between these extremely low values and the predetermined high value at which the relatively 40 abrupt voltage droop is to occur, the element 17 begins to saturate thereby increasing the reluctance of this element and producing the equivalent of an air gap at 11. Consequently, leakage flux is produced and this flux tends to compensate for the increasing reluctance of the section 12, as it 45 begins to saturate with increases in current. Consequently, as the droop producing action of the increasing saturation of the restricted section 12, and the compensating action of the leakage flux producing saturable element 17, both operate on 50 the principle of saturation and are both non-linear, they tend more nearly to neutralize each other throughout the range of intermediate current values. When the predetermined high value 55 of current is attained the element 17 becomes practically completely saturated, and hence it has little or no effect in increasing the leakage flux so that the further saturation of the element 12 produces the desired relatively abrupt droop in voltage. 60

In Fig. 2, the solid curve shows the improved characteristic obtained by my invention. As shown, the section abc of the curve is substantially a straight horizontal line showing that substantially constant voltage is maintained over the desired current range, and for current values above c there is a relatively abrupt droop in voltage. The upper dotted curve shows the type of characteristic which would be obtained if the element 17 were omitted. In that curve the action 65 of the leakage flux produced during the low and intermediate values of current by the relatively high reluctance of the air gap 11 is such as to overcompensate for the low values of reluctance 70 75

of section 12 and consequently a voltage rise is obtained. The lower dotted curve shows the characteristic which would be obtained if the air gap 11 were omitted entirely and there were no saturating element 11. This curve shows that beyond very low values of current the gradually increasing reluctance of the section 12 before it reaches the knee of its saturation curve is sufficient to produce an objectionable premature voltage droop.

While I have shown and described a particular embodiment of my invention, it will be obvious to those skilled in the art that changes and modifications may be made without departing from my invention and I therefore aim in the appended claims to cover all such changes and modifications as fall within the true spirit and scope of my invention.

What I claim as new and desire to secure by Letters Patent of the United States is:

1. In combination, an electromagnet armature and two magnetic circuits each including said armature, one of said circuits having a variable reluctance magnetically saturable flux by-pass around said armature, said one circuit also including a variable reluctance magnetically saturable element whereby a controlled leakage flux threading the other circuit is produced.

2. In combination, an electromagnet armature and three magnetic circuits each including said armature, the first circuit including a variable reluctance magnetically saturable section, the second circuit utilizing said section as a flux bypass around said armature, the second circuit including a magnetically saturable element, and the third circuit containing leakage flux from the second circuit which varies with the reluctance of said saturable element.

3. In combination, an electromagnet comprising a core member, an armature and a direct current exciting winding, an additional electromagnet comprising an additional core member, a part of the first core member, an additional direct current exciting winding and a magnetically saturable element, said additional electromagnet and said saturable element being so arranged with respect to the first electromagnet that when said element saturates it produces a leakage flux from said additional electromagnet which acts on the armature of the first electromagnet in a manner to weaken the action of the first electromagnet thereon.

4. In combination, an electromagnet core having two pole faces, an armature cooperating with said pole faces, an effective pivotal support for said armature nearer one end thereof than the other, a direct current energized winding for producing a flux which enters said armature from the pole face of said core which is farthest away from said support, a second core member whose magnetic circuit includes a portion of said first core member which is adjacent said last mentioned pole face, a direct current energized wind-

ing for producing a flux in said second core member which traverses said portion of said first core member in a direction opposite to said first mentioned flux, and a magnetically saturable element in the path of said last mentioned flux where it enters said first mentioned core member.

5. A voltage regulator having, in combination, current responsive means including a magnetically saturable element for changing the calibration of said regulator with changes in current in 10 accordance with the magnetic saturation of said element, and means including a second magnetically saturable element for neutralizing the calibrating effect of said current responsive means during the early stages of the saturation of the 15 second saturable element.

6. A vibratory contact generator voltage regulator having, in combination, current responsive flux producing means including a magnetically saturable element for reducing the voltage which 20 said regulator will hold as the current increases in accordance with saturation of said element, and means including a second saturable element for producing a controlled leakage of the flux produced by said current responsive means which is 25 sufficient to neutralize the effect of said first saturable element during the early stages of its saturation.

7. In combination, a direct current shunt generator, a vibratory contact voltage regulator for 30 said generator, means including a magnetically saturable element responsive to the current of said generator for causing the voltage held by said regulator to droop as the current increases, 35 and means including another magnetically saturable element for substantially neutralizing the effect of said current responsive means at current values below a predetermined value.

8. An electric regulator having an operating element, a voltage responsive means for producing a magnetic flux for actuating said operating element, a current responsive means for modifying the magnetic flux produced by said voltage responsive means non-linearly with the current traversing said current responsive means, and 45 means in operative relation with said current responsive means for varying its modifying action non-linearly with the current traversing said current responsive means.

9. In a regulator having voltage responsive 50 means and current responsive means cooperating for causing said regulator to hold a substantially constant voltage up to a predetermined value of current traversing said current responsive means and wherein said current responsive means 55 causes a non-linear drop in the value of voltage maintained, the combination with said current responsive means of means for modifying the action of said current responsive means non-linearly with the current therethrough for substantially exactly compensating for said voltage drop.

BERNARD M. CAIN.
